J. J. McINTYRE

WINDOW

Filed Feb. 3, 1925

INVENTOR,
John J. M^{sc}Intyre,
BY
R. S. Burns
ATTORNEY

UNITED STATES PATENT OFFICE.

JOHN J. MCINTYRE, OF LOS ANGELES, CALIFORNIA.

WINDOW.

Application filed February 3, 1925, Serial No. 6,503.

To all whom it may concern:

Be it known that I, JOHN J. MCINTYRE, a citizen of the United States, residing at Los Angeles, in the county of Los Angeles 5 and State of California, have invented new and useful Improvements in Windows, of which the following is a specification.

This invention particularly pertains to the construction of casement windows of the 10 type in which the window sash is mounted on hinges to swing horizontally, and also adapted to be moved vertically on its hinges so that the sash may be positioned with its lower end seating on a window ledge and 15 be adapted to be lifted so as to swing inwardly clear of the inside window sill. In windows of this type it is necessary to provide a space in the upper portion of the window frame to permit of the vertical 20 movement of the sash and in order that the sash may swing it is necessary that this space open to the front of the window frame, which, when the sash is closed, forms an unsightly gap between the upper edge of the 25 sash and the top member of the window frame.

The primary object of the present invention is to provide a means for filling the 30 gap at the top of the sash when the latter is closed, which is operable to permit vertical movement of the sash.

Another object is to provide a device of 35 the above character which is simple in construction and adapted to be readily installed.

A further object is to provide a device 40 of the above character which is efficient in operation and is not liable to get out of order.

With the foregoing objects in view, together with such other objects and advantages as may subsequently appear, the 45 invention resides in the parts and in the combination, construction and arrangement of parts hereinafter described and claimed and illustrated by the way of example in the accompanying drawings, in which—

Figure 1 is a view of a casement window in side elevation with parts broken away, illustrating the application of the invention;

Figure 2 is an enlarged detail as seen on the line 2—2 of Figure 1;

Figure 3 is a detail in section of the upper portion of a window frame and sash illustrating the operation of the invention;

Figure 4 is a detail in perspective illus-

trating the manner of constructing and mounting the filler strip.

Referring to the drawings more specifically, 5 indicates generally a window frame and casing of ordinary construction in which 60 is mounted a sash 6 carried on hinges 7 and 8; the sash being hinged to swing horizontally. The window frame and casing embodies the usual inside sill 9 and outside 65 sill 10, the latter being formed with a ledge 11 spaced below the top of the sill 9 to form a vertical shoulder 12 at the juncture of the sill 9 with the ledge 11. The sash 6 is designed when closed to be seated on the ledge 11, as particularly shown in Figure 2, with 70 the inner face of the lower end of the sash extending alongside the shoulder 12, and the hinges 7 and 8 are so formed as to permit the sash being moved vertically so that the lower end thereof may be positioned above 75 the top of the inside sill 9 to permit the sash being swung to an open or closed position over the inside sill. For this purpose I preferably employ the hinge construction 80 shown in United States Letters Patent Number 1,517,792, issued to me under date of December 2, 1924, which type of hinge embodies a pair of leaves pivotally connected together by a pintle 13 and adapted to be shifted vertically in relation to each other 85 on the pintle; one of the hinged leaf members being affixed to the window sash and the other leaf being attached to a side member of the window frame or casing.

In carrying out the present invention the 90 top member 14 of the window frame is spaced above the upper edge of the window sash so as to afford such clearance that the sash may be moved vertically when in its closed position, and also to provide a space 95 15 to accommodate a filler strip 16 adapted to normally fill a gap 17 extending between the upper edge of the closed sash and the top panel 18 of the window casing; the panel 18 being arranged to extend below the top 100 window frame member 14 with its lower edge so positioned in relation to the upper edge of the sash 6 that when the sash is disposed in its uppermost position it may swing beneath the top casing panel 18 and out of 105 its closed position.

The filler strip 16 is preferably formed of wood and is substantially quarter-round in cross section, it having a flat under face 19 adapted to seat on the upper edge of the sash 110

6 and having a flat front face 20 adapted to extend in alignment with the front surface of the top rail of the window sash. The filler strip 16 is of a length substantially corresponding to the width of the window sash, and is formed with end trunnions 21 and 22 which extend into vertical slots or channels 23 and 24 formed in the upper end portions of the side members 25 and 26 of the window frame; the slots 23 and 24 having their lower ends terminating on a plane slightly above the lower margin of the top casing panel 18 to form shoulders or ledges on which the trunnions 21 and 22 are adapted to seat; and the slots or channels being of such length that the filler strip may be moved vertically therein a distance substantially equal to that of the vertical travel of the sash 6.

20 The filler strip 16 normally gravitates into the depending position shown in Figures 2 and 4 with the front face 20 thereof abutting against the rear face of the top casing member 18 which serves as a stop to normally dispose the filler strip with its front face extending vertically.

In the operation of the invention, when the window sash is in its closed position, as shown in Figures 1 and 2, the lower edge 30 of the sash will seat on the ledge 11 with the inner face of the lower rail of the sash abutting against the shoulder 12 of the inside window sill 9. The upper end of the window sash will then be disposed below the lower edge of the top edge of the casing panel 18, and the filler strip 16 will be seated on the upper end of the sash with its front face 20 spanning the gap 17, and thereby closing the latter. When it is desired to open the window the sash is moved vertically, while in a closed position, on its hinges, which may be accomplished in any desired manner, but is here shown as effected by means of an operating lever 40 27 embodied in the hinge 8 as set forth in the patent above referred to. The upward movement of the sash lifts the filler strip 16 therewith which movement of the filler strip is guided by the trunnions 21 and 22 45 thereon riding in the guide slots 23 and 24. When the sash is in its uppermost position the filler block will be disposed as indicated by the dotted line *a* in Figure 2. The sash is then raised such distance that its lower edge 50 is below the lower edge of the top window casing 18. When thus positioned the sash may be swung on its hinges into an open position.

On swinging the sash outwardly on the 60 hinges to a point where the upper edge thereof will pass from beneath the filler strip 16 the latter will gravitate downwardly and come to rest with the trunnions seating on the shoulders formed at the lower ends of the slots 23 and 24. On then

moving the sash to its closed position, the inner upper margin of the sash at the hinged side thereof will strike the vertical face 20 of the filler strip at a point immediately below the trunnions and on continued closing movement of the sash will operate to rock the filler strip on the trunnions so that when the sash is in its normal position and still in its elevated position, the filler strip will lie on the upper edge 75 of the sash with the face 20 seating thereon, as indicated by the dotted lines *b* in Figure 3. On then lowering the sash to its closed position, the filler strip will rock downwardly from the position shown in dotted lines *b* in Figure 3, into its normal position shown in Figures 2 and 4, thereby closing the gap 17.

It will be understood that while I have shown the invention as applied to a casement window of the single sash type it is equally applicable for use on a double casement window, as the opening or closing of either of the sash of a double casement window will actuate the filler strip in the manner set forth; and that while I have specifically described the invention as applied to a casement window, it is equally applicable for use with doors and hinged closures in general, in which the closure is adapted to be shifted vertically on its hinges.

While I have shown and described a specific embodiment of the invention I do not limit myself to the exact details of construction and arrangement shown, but may make such changes and modifications therein as occasion may require coming within the meaning and scope of the appended claims.

I claim:—

1. In a window, a window frame including a top member, and side members; a sash hinged to said frame to swing horizontally and adapted to be shifted vertically, there being a gap between the upper edge of the sash and the top member of the frame, and a filler strip arranged in the gap and extending between the upper edge of the sash and the top frame member, said filler strip being mounted to slide vertically and to rock horizontally.

2. In a window, a window frame embodying a top member and side members; a sash hinged to swing horizontally and adapted to be shifted vertically in said frame, there being a space between the upper edge of the sash and the top frame member, a filler strip arranged in the said space, and trunnions on said filler strip extending into vertical slots in the side frame members whereby said filler strip may be moved vertically and rocked horizontally.

3. In a window, a window frame including a top member and side members; a sash hinged to swing horizontally in said frame and adapted to be shifted vertically, there

being a space between the upper edge of the sash and the top frame member, a filler strip arranged in said space adapted to seat on the upper edge of said sash when the latter is in its closed and lowermost position, trunnions on said strip, and guideways on said frame side members on which said trunnions are mounted to slide, and whereby said filler strip may be moved vertically and swung horizontally.

4. In a window, a frame having top member and side members, vertical guideways in the upper portions of said side members, a filler strip extending parallel to the top

frame member having its ends supported in said guideways for vertical and pivotal movement, and a sash hinged to said frame to swing horizontally and adapted to be shifted vertically, said filler strip normally depending from said guideways and arranged to be engaged by the upper edge of the sash so as to be rocked horizontally when the sash is moved inwardly to a closed position; said filler strip being operable on moving the sash downwardly in its closed position to swing downwardly into a seated position on the upper edge of said sash.

JOHN J. McINTYRE.
